UNITED STATES PATENT OFFICE.

PHILIPPE A. DESLAURIERS AND LOUIS P. DESLAURIERS, OF ST. PAUL, MINNESOTA, ASSIGNEES, BY MESNE ASSIGNMENTS, TO PHILIPPE A. DESLAURIERS AND LOUIS P. DESLAURIERS, COPARTNERS DOING BUSINESS UNDER THE FIRM-NAME AND STYLE OF DESLAURIERS COLUMN MOLD COMPANY, OF ST. PAUL, MINNESOTA.

COLUMN-MOLD.

1,039,498.

Specification of Letters Patent. Patented Sept. 24, 1912.

Application filed July 6, 1909. Serial No. 506,002.

To all whom it may concern:

Be it known that we, PHILIPPE A. DESLAURIERS and LOUIS P. DESLAURIERS, citizens of the United States, residing at St. Paul, 5 in the county of Ramsey and State of Minnesota, have invented certain new and useful Improvements in Column-Molds, of which the following is a specification.

Our invention relates to means for constructing concrete columns wherein a divided casing or mold is employed and consists particularly in improved means for securing and holding the mold in position for receiving the concrete.

15 To this end our invention consists in the features of construction and combination hereinafter described and claimed.

In the accompanying drawings forming part of this specification: Figure 1 is a perspective view of our invention, Fig. 2 is a section on line $\alpha-\alpha$ of Fig. 1, Figs. 3 and 4 are top and perspective views, respectively, of clamping means for holding the mold in position; Fig. 5 is a perspective view of a section of a mold illustrating our improved means for securing the same in position for receiving concrete. Fig. 6 is a top view of the same, Fig. 7 is a detail view of a part of the clamping means.

30 In the drawings the mold is shown made up of a main sheet 2 and an extension sheet 3, adjustably connected, and the whole bent into the shape of the column to be formed; the free edge 4 of the main sheet is bent 35 outwardly and rearwardly as indicated best in Fig. 2, and a flange or iron 5 extends longitudinally along the adjacent portion of the extension plate 3 and is bent outwardly and formed at its outer edge with a lip 6, 40 underneath which the flange 4 is adapted to fit.

For the purpose of holding the mold closed we provide templet frames each consisting of a split ring B, the ends 7 of the 45 ring portions being bent outwardly and formed with openings 8 through which bolts 9 may be passed.

In Fig. 4 we show a clamping device for the ends 7 to be used in substitution for or 50 in connection with the bolts 9. This clamping device consists of a plate 10 formed with parallel slots 11 inter-spaced to receive the ends 7. The tongue 12 of the plate,

intermediate of the slots is preferably bent rearwardly to allow the ends of the ring to 55 be drawn together after the plate is in position.

B' represents a device for drawing the ends of the ring together as illustrated in Fig. 5. This consists of a handle pivotally 60 supporting at one end a block 13 formed with a pin 14, fitted to one of the openings 8, an arm 15 having pivotal support 16 at the rear of said block and pivotally supporting at its free end a block 17 corre- 65 sponding to the block 13 and formed with a similar pin.

In applying each templet frame adjacent ends 7 may be first secured together on the opposite sides of the flanges 4 and 5 as by 70 the bolt 9, leaving the opposite ends of the ring unconnected. The device B' is then employed with the pins 14 extending through the openings 8 in the free ends 7 and the handle of the device B turned to 75 one side to draw together the free ends 7 of the ring; when drawn sufficiently together the clamping plate 10 will be dropped over the ends 7 back to the blocks 13, as illustrated in Fig. 4, and the device B removed. 80 The device B and the clamping plate 10 thus coöperate to allow the free ends of the templet frames to be drawn together and clamped in adjusted position.

By means of the features of construction shown and described we secure a mold which will be firmly clamped in position to receive the concrete entirely by means of the templet frames. Tightening of the templet frames upon the mold will squeeze 90 the flange 4 within the angle iron 5, making a tight joint between said flange and angle iron and rendering unnecessary the use of any securing means passing therethrough.

We claim:

1. The combination with a split mold of the class described, one edge of said mold being turned outwardly and rearwardly with its edge interspaced from the mold, and a flange constructed to receive said bent edge 95 arranged longitudinally along the opposite free edge of the mold, the edge of the mold carrying said flange underlapping said bent edge, the portion of said flange which overlaps the rearwardly-bent edge being off-set 100 with respect to the meeting edges of the

mold, whereby a wedging action is produced at the joint, of means surrounding the mold for compressing said flange upon said bent edge.

- 5 2. The combination with a split sheet metal mold of the class described having one of its edges outwardly and rearwardly directed, said edge being interspaced from the adjacent portion of the mold, and a flange 10 carried by the other edge of the mold and extending outwardly and forwardly over the rearwardly-directed edge, the edge of the mold carrying said flange underlapping said bent edge, the portion of said flange 15 which overlaps the rearwardly-directed edge being off-set with respect to the meeting edges of the mold, whereby a wedging action

is produced at the joint, and means for clamping the rearwardly-directed edge within said flange comprising a templet frame 20 surrounding said mold, said templet frame having outwardly-bent portions upon opposite sides of said flanges, means for contracting the templet frame, and means for holding the templet frame in contracted position 25 upon the mold.

In testimony whereof we affix our signatures in presence of two witnesses.

PHILIPPE A. DESLAURIERS.
LOUIS P. DESLAURIERS.
